CLAIM

The ornamental design for a dispenser for bubble gum or other encapsulated articles, substantially as shown and described.

DESCRIPTION

FIG. 1 is a front perspective view of a dispenser for bubble gum or other encapsulated articles showing my new design, the broken lines being for illustrative purposes only;

FIG. 2 is a right side elevational view thereof;

FIG. 3 is a front elevational view thereof;

FIG. 4 is a rear elevational view thereof;

FIG. 5 is a top plan view thereof;

FIG. 6 is a left side elevational view thereof;

FIG. 7 is a bottom plan view thereof;

FIG. 8 is a front elevational view of a second embodiment of a dispenser for bubble gum or other encapsulated articles;

FIG. 9 is a left side elevational view of the embodiment of FIG. 8; and

FIG. 10 is a top plan view of the embodiment of FIGS. 8 and 9.

FIG. 1

FIG. 2

FIG. 3

FIG. 4

FIG. 6

FIG. 5

FIG. 7

FIG. 8

FIG. 9

FIG. 10
